Primary Examiner — Susan Bennett Hattan*Assistant Examiner* — Leanne Was(74) *Attorney, Agent, or Firm* — King & Schickli, PLLC(57) **CLAIM**

The ornamental design of an optical lens, as shown and described.

DESCRIPTION

FIG. 1 is a perspective view of an optical lens;

FIG. 2 is a top view of the optical lens;

FIG. 3 is a bottom view of the optical lens;

FIG. 4 is a right side view of the optical lens;

FIG. 5 is a left side view of the optical lens;

FIG. 6 is a front view of the optical lens;

FIG. 7 is a rear view of the optical lens; and,

FIG. 8 is a perspective view of the optical lens in a particular environment, such as a light bar.

The broken lines depict environment that forms no part of the claimed design.
